C. J. CARTER

FLOORING

Filed July 22, 1922

INVENTOR

Charles J. Carter

BY
Arthur G. Brown

ATTORNEY

Patented Sept. 9, 1924.

UNITED STATES PATENT OFFICE.

CHARLES J. CARTER, OF KANSAS CITY, MISSOURI.

FLOORING.

Application filed July 22, 1922. Serial No. 576,878.

To all whom it may concern:

Be it known that I, CHARLES J. CARTER, a citizen of the United States, residing at Kansas City, in the county of Jackson and State of Missouri, have invented certain new and useful Improvements in Flooring; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to flooring and particularly to a unit which may be so constructed at the factory that it may be laid down on a support or foundation in an expeditious and convenient manner.

20 Certain types of wooden floors are laid down in units, each unit consisting of a base board to which is fastened a plurality of floor blocks. The base boards are generally laid down with their fibers running in the usual way, that is, from end to end. The floor blocks, however, have their fibers running vertically since they offer better resistance to wear and tear when the ends of the fibers are subjected to the wear than when the fibers run longitudinally of the units. With such a construction it is usually the practice to key the block sections together with the side edges of the blocks grooved so that the sections may be keyed together by strips which enter aligning grooves of adjacent sections. Then nails are driven through the blocks of one section, and through its keyed strip into the blocks of an adjacent section.

40 My invention contemplates building a floor section in which the nails are introduced into the section before the section or unit leaves the factory. Then it is only necessary to drive the nails "home"; that is, drive them into an adjacent section to build up the floor.

If the nails are properly set in the sections before the sections leave the factory, they can be driven in straight so that their points practically penetrate the sections, the extreme points, however, being just inside the skins of the sections so that when the sections are set in place, unskilled labor can be used to drive the nails into the keying strips and into the adjacent section in a convenient manner.

My invention, therefore, is confined to a floor section or unit having the nails initially driven into it so that the nails practically but not quite penetrate the section and with the heads of the nails projecting in grooves so that the tool for driving the nails "home" automatically finds them as it is moved along the grooves; the nails being long enough so that when they are driven "home" they may penetrate the keying strip and enter the next section to which the nail-carrying section is to be secured.

50 The novel construction of the invention will be clearly understood by reference to the following description in connection with the accompanying drawings, in which Fig. 1 is a perspective view of a floor section constructed in accordance with my invention.

Fig. 2 is a cross sectional view on the line 2—2 of Fig. 1, and

Fig. 3 is a horizontal sectional view through a plurality of floor sections, the nails in one section being shown as penetrating a key strip and entering the adjacent section and the nails in another section being shown ready to enter the keying strip and a previously laid floor section.

55 In order to disclose my invention I shall refer to it in connection with a known type of flooring.

The numeral 1 designates a base board or strip having on its upper face a plurality of longitudinally disposed tongues 2, to provide dove-tailed grooves 3. The tongue-and-groove portion of the strip 1 inter-engages a similar tongue-and-groove portion 4 on each block 5, the blocks being slid onto the strip from its end or ends.

60 In practice I prefer to form the blocks so that the fibers will run from the bottoms of the blocks to the tops so that the ends of the fibers provide the wearing surface for the floor section. This arrangement, however, specifically is not a part of the present invention as such a construction has been employed heretofore.

65 The blocks have their side edges, front and back, provided with aligning grooves 6 and 7, the grooves running transversely of the blocks but longitudinally of the section so that elongated front and back grooves are provided for the section, as will be clearly apparent by reference to Fig. 1. The front 70 sides of the respective blocks are provided with recesses or countersunk portions 8, ap-

proximately co-extensive with the heads 9 of the nails 10. The recesses or countersunk portions 8 extend approximately half-way through the block. In actual practice this may be more or less dependent upon the length of the nails.

The nails are introduced concentrically of the countersunk or recessed portions 8 and are driven into the block until their points 11 are practically to the surface of the walls 12 of the grooves 7 and their heads extend out of the recessed portions 8 and lie in the grooves 6 or outwardly from the wall portions 13 of the grooves 6. The purpose of permitting the nail shanks to extend across the grooves 6 is to allow a punching tool or nail set to be introduced into the elongated groove formed by the aligning grooves 7 to automatically find the nail. 20 Then the set can be operated to drive the nail.

Each key strip 14 is approximately twice the width of a groove 6 or 7; that is, half of the width of the key strip 14 is substantially equal to the width or depth of each groove so that when the sections are brought together, as shown in Fig. 3, the key strips 14 will key into both grooves to lock the two together so that liability of warping will be eliminated and so that the two sections can be fastened together when the nails from one section are driven through the intermediate strip into the next section.

When the sections are formed in the factory, they will be shipped to the building in which they are to be laid in substantially the form shown in Fig. 1. The base board or strip 1 of the first section can be secured to its foundation by nailing or it may rest directly upon a concrete foundation. The first strip can be laid next to the wall of the building; then a key strip will be inserted in the grooves 6, and then another section similar to 1 will be positioned next to it with the grooves 7 receiving half of the key strip 14. A nail set can then be run along the aligning grooves 6 until it comes into contact with a nail. The nails can be driven "home" so that the second section will be fastened to the first. Another key strip 14 will then be introduced into the aligning grooves 7 of the blocks of the second section and a third section can be lined up after the manner of the first and second. Then the nails will again be driven "home."

In Fig. 3 I have shown a section A consisting of the blocks with the nails driven "home." This section A is fastened to a section B by the key strip C, the nails in the

section B being driven "home." The section D is keyed to the section B by strip C' but the nails are in position to be driven through the key strip C' into the blocks of the section B. It is understood, of course, that the sections A, B and D are all constructed in accordance with Fig. 1 and that the key strips C and C' are the key strips 14.

It will be apparent from the foregoing that the floor sections may be economically arranged at the factory where there is skilled labor and where the construction of the sections may be under competent direction. Then they can be shipped to the buildings where they are to be used so that the floor can be laid quite inexpensively by unskilled labor without requiring any knowledge of the construction of the floor section, it being only necessary to operate a nail set in order to lay down the sections edge to edge.

It will be observed that I do not provide nails in all of the blocks. Certain blocks in each section may be provided with a nail and the nails in one section will not align with the nails in another section, as clearly seen in Fig. 3, so that when the nail point from one section penetrates another section, it will go directly into a block rather than into a recess, thereby insuring a rigid construction when the floor has been completed.

For the purpose of illustration I have shown my invention as applied to a known type of floor, but I do not wish to be limited to this particular type of flooring as the sections may be made of solid strips or units and secured together in substantially the same manner as if they were formed in the manner shown.

What I claim and desire to secure by Letters-Patent is:

As an article of manufacture a floor section 100 consisting of a base strip, a plurality of blocks mounted on the base strips, the blocks having aligning grooves in their opposite vertical faces for receiving splines, some of the blocks each having a recess opening 105 from the base of one of its spline grooves and terminating short of the opposite groove, nails extending through said recesses into the block material with their heads projecting into one spline groove and their points 110 terminating short of the other spline groove, whereby when the section is laid against a like section the nails may be driven on through the blocks and through a spline into the abutting blocks of said like section. 115

In testimony whereof I affix my signature.

CHARLES J. CARTER.
